GARMENT SEAM

Robert Goldsmith, Orange, N. J.

Application July 17, 1934, Serial No. 735,622

10 Claims. (Cl. 112—262)

This invention relates to garment seams.

One object of this invention is to provide an improved seam for garments or other seamed articles made of textile fabrics of a rather delicate or weak texture, wherein a pull on the seam shall not result in separation of the yarns at the seam nor in a ripping of the same.

Another object of the invention is the provision of an improved seam which is simple in construction, inexpensive to manufacture, durable, reliable, efficient in use, neat and compact in appearance, and an improved method of manufacturing the seam.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

Figure 1 is a plan view showing the first step in the manufacture of the seam.

Fig. 2 is a plan view showing the second step of making the seam, the latter embodying the invention.

Fig. 3 is a plan view showing the front side of the seam.

Fig. 4 is a cross sectional view of the seam taken on line 4—4 of Fig. 2.

Fig. 5 is a plan view of a modified seam.

Fig. 6 is a cross sectional view of the seam taken on line 6—6 of Fig. 5.

Fig. 7 is a plan view showing the first step in the making of a seam by a different process.

Fig. 8 is a plan view showing the second step.

Fig. 9 is a plan view showing the third step.

Fig. 10 is a plan view showing the last step and the seam embodying the invention.

Fig. 11 is a sectional view taken on the line 11—11 of Fig. 10.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes a seam for garments and the like embodying the invention. The seam may include two sections of material 11 and 12 having opposing margins turned back upon themselves in opposite directions and constituting complementary folded edge portions 11a and 12a respectively lying in edge to edge abutment and interconnected through single thicknesses of the edge portions at their folds by an ordinary straight line of stitching 13. 10 An overlapping or zigzag stitching interconnects the said sections, by passing through four layers of the material, including the folded edge portions. Such stitch formation passes perpendicularly along spaced lines through the respective 15 edge portions sufficiently far back of the fold lines to leave adequate intervening fabric in each of the plies to absorb strain imposed on the stitches when the seam is subjected to tension. That is to say, the stitches penetrate the surface 20 beyond the edge extremity and the immediate curved area of the fold. The zigzag stitching extends along and makes binding engagement with both the top and bottom exposed surfaces of the edge portions at the seam, and the stitches 25 extend transversely of the seam from one edge portion to the other opposite the inner line of stitching 13 at both surfaces so as to distribute strain between the top and bottom plies of the 30 two edge portions.

It may be further pointed out that the stitching 14 completely encompasses within its confines the fabric back of the edge folds of all plies of both of the oppositely folded edge portions in the area of the inner stitching 13, and cooperates with the stitching 13 to prevent concentration of stresses 35 at the seam in single plies of either edge portion.

To make the seam, the two sections of material are laid over each other, with their edges, straight or pinked, in coincidence as shown at 15. When 40 the seam is used in women's underwear, the edges 16 are usually pinked, but this has been omitted to render the drawing clearer. Then the line of stitching 13 is formed spaced from 16. Next the sections are laid out flat as shown in Fig. 2, and 45 the edge portions folded flat away from each other, in which condition the encompassing line of stitching 14 is applied.

It will be noted that the yarn can be as strong as desired, the strength of the seam being determined by that of the fabric. By this invention twice as many layers of the fabrics are caught in the stitching as heretofore. Further, the stitching acts at longitudinally spaced and transversely offset points of the seam, so that a cross- 50 55

wise pull on the seam is distributed in such a way as to reduce the tendency to separation of the 5 yarns of the fabric to the degree where holes result, as in seams heretofore used. The width of the zigzag line of stitching is very small, and may be less than one sixteenth of an inch, and the zigzag angle may be approximately 45 degrees. The different lines of stitching supplement and strengthen each other. In general, it may be 10 said that the cross stitching 14 passes through the folded edge portions of the sections 11 and 12 back of the fold lines, the stitching passing through the main and fold plies of the sections at right angles, and preferably along lines equally 15 spaced from the line of stitching 13, that is the points at which the cross stitching passes through a main ply and its fold ply desirably being equidistant from the fold lines of the respective edge portions. Hence, a sufficient number 20 of yarns of the fabric in each ply of each edge portion will intervene between the lines of penetration of the stitching 13 and 14 in both the main and fold plies to distribute the stress caused by the stitching when a pull is exerted on the seam. 25 However, the lines of penetration of stitching 13 and 14 are in sufficiently close proximity that the number of intervening yarns of the fabric in the several plies will not be so great as to prevent the stitching 14 from acting in supplemental reinforcing relation to the stitching 13.

In Figs. 5 and 6 is shown a modification of the invention including a seam which is similar to that shown at 10, except that the seam includes a double overlap of the opposing sections 18, 19 thereof. Thus instead of folding along the line 35 of stitching 13, the sections are folded in spaced relation thereto at one or at opposite sides of said line as shown at 20, 21 before the zigzag line of stitching 14 is formed. In other words, the fold portion 19a of section 19 is folded spaced from line 13, and section 18 is folded in spaced relation to said line. Then the stitching 14 is applied to the four overlapping layers, producing eight 40 points of engagement of the stitching thread with the fabric at the seam, and encompassing and binding together fabric of both layers of the respective edge portions in the area of the inner line of stitching 13.

In Figs. 7 to 11 is shown a further modification 50 of the invention, in which the fold lines 20, 21 of Fig. 6 are automatically fixed so that the use of the hands or of machine attachments for this purpose are unnecessary. Hence the pieces of fabric 23, 24 are superimposed as shown at 55 25, as in Fig. 1, with edges 26 in coincidence if desired, and a criss cross or zigzag or similar stitching 27 employed spaced from said edges, it being sufficient that a portion of desired width, that is, the width of the stitching, be secured. Now 60 the fabric pieces are spread flat as at 28, with the folded portions 23a and 24a of the respective sections folded over on one side. Then the fold portion is folded back as shown at 29. It will now be seen that there are two fold lines, 65 the fold line 30 in section 24 and the fold line 31 in section 23 or fold 23a. These fold lines are along and against the opposite edges of the stitching 27. In this condition, a straight, or an overlapping or zigzag line of stitching 32 is formed 70 closely along the fold line 31, and hence in the region of and superimposed on the stitching 27. In cross section the overlapping will appear as in Fig. 11. The stitching 32 may be of the same or slightly less width than the stitching 27. The latter may be a hemstitch, as the same is stronger,

although slower in sewing than a zigzag so as to render the same fully inconspicuous.

The resulting seam 33 embodying the invention has a high degree of strength and possesses a degree of elasticity.

The invention can be used regardless whether the seam be along the bias or straight with the weave of one or both fabric sections. Its advantages are especially marked if the fabric be cut straight.

The invention solves one of the most difficult and perplexing problems in the provision of a suitable strong seam for women's lingerie of the cheaper kind and made of delicate inexpensive material. It is applicable also to false seams 15 formed in one piece of fabric.

It will be appreciated that various changes and modifications may be made in the device as shown in the drawing, and that the same is submitted in an illustrative and not in a limiting sense, the scope of the invention being defined in the following claims.

I claim:

1. A stitched seam for articles made of a delicate textile fabric, and whereby the formation 25 of openings in the fabric by slippage of the yarns is substantially prevented, including a plurality of woven fabric sections having at their edges main portions and fold portions in abutment with each other along their fold lines, a line of stitching interconnecting the sections along the fold lines between the main and fold portions, and a cross stitching extending along both surfaces of the seam and passing through the main and fold portions along spaced lines lying spaced back of 35 the fold lines, said cross stitching passing back and forth across the fold lines of these sections at both surfaces of the seam and passing through the main and fold portions of each section at equal distances from the fold line of the section.

2. A stitched seam construction for sections 40 of delicate textile fabric and especially adapted for women's underwear, including a plurality of woven fabric sections having opposing margins respectively folded back upon themselves in opposite directions and constituting complementary 45 plied edge portions, an inner line of stitching extending through and joining single thicknesses of the respective edge portions, and a stitch formation 50 penetrating the several plies of the respective edge portions intermediate the edge folds and the free edges of the turned back ply, said stitch formation making two closely spaced lines of penetration with the fabric, and said stitch formation including connecting stitch portions at both exposed surfaces of the seam between the lines of penetration so as to encompass within the confines of the stitch formation fabric of each ply of each edge portion along the inner line of stitching.

3. A stitched seam construction for sections 60 of delicate textile fabric and especially adapted for women's underwear, including a plurality of woven fabric sections having opposing margins respectively turned back upon themselves in opposite directions and constituting complementary 65 folded edge portions, an inner line of stitching extending through and joining single thicknesses of the respective edge portions, and a zigzag stitch formation adapted to distribute stresses 70 between all the plies of the respective edge portions extending back and forth at the opposite exposed surfaces of the seam and penetrating all the plies of the respective edge portions in spaced relation to their folded edges at both surfaces of the seam and encompassing within the forma- 75

tion the areas of the plied edge portions along the inner line of stitching.

4. A stitched seam for articles made of relatively delicate textile fabric, and whereby the formation of openings in the fabric by slippage of yarns under seam tension is substantially prevented, including a plurality of woven fabric sections having at their edge portions fold plies extending away from each other and lying against the main ply of the corresponding edge portion at one surface thereof, a line of stitching interconnecting single thicknesses of the respective edge portions, and a zigzag stitching interconnecting and binding together the main and fold plies of the respective edge portions, said zigzag stitching passing back and forth across the exposed opposite surfaces of the seam opposite the first line of stitching, and passing through the main and fold plies of each section at points spaced at both exposed surfaces of the seam from the fold lines of the sections, and also spaced from the line of engagement of the first stitching, with the number of yarns of the plied fabric interposed between the lines of penetration of the first and second mentioned stitchings sufficient to distribute a stress at the seam between the several plies of each edge portion but not so great as to prevent the holding power of one stitching from supplementing that of the other.

5. A stitched seam for a plurality of sections of delicate textile fabric and especially adapted for women's underwear, whereby the formation of openings in the fabric by slippage of yarns under seam tension is prevented, including a plurality of woven fabric sections having at their edges fold plies extending away from each other and so as to lie against the main plies of the corresponding sections, the fold lines of the edge portions lying in proximity to each other, a line of stitching interconnecting the edge portions along their fold lines, and a cross stitching passing through and binding the respective fold and main plies of each edge portion together and to the plies of the other edge portion along lines which at both exposed surfaces of the seam are equally spaced back of the fold lines, said cross stitching passing back and forth at both surfaces of the seam across the fold lines of the sections and interconnecting the plied edge portions together at both surfaces of the seam, whereby the seam tension is absorbed by the first and second stitchings and through the second stitching is distributed between the several plies of each edge portion.

6. An edge-folded, trimmed and zigzag stitched seam, substantially flat on its normally exposed surface, comprising at least two sections of fabric, each section having a trimmed and flat edge

folded against the normally concealed surface of the garment, said folded and trimmed edges lying flat and facing in opposite directions on said sections of fabric and being stitched together by a single line of zigzag stitching passing through the pre-folded edges of the folded sections of fabric.

7. An edge-folded and zigzag stitched seam, substantially flat on its normally exposed surface, comprising at least two sections of fabric, each section having a flat edge folded against the normally concealed surface of the garment, said folded edges lying flat and facing in opposite directions on said sections of fabric and being stitched together by a single line of zigzag stitching passing through the pre-folded edges of the folded sections of fabric.

8. A stitched garment seam construction for fine textured garment fabric adapted to overcome the tendency of such fabric when under strain to rupture at a seam comprising sections of delicate garment fabric having folded back edge portions, said edge portions extending in opposite directions from their fold lines and each lying flat against its section on the normally concealed side thereof, and a zigzag stitch formation passing through the folded fabric plies along closely spaced parallel stitching lines located slightly back of the fold lines at both faces of the seam and remote from the extremities of the folded back edge portions.

9. A stitched garment seam comprising adjoining fabric garment sections having edge portions provided with non-raveling pinned edges, each edge portion being folded back and lying flat against its section on the normally concealed surface of the fabric with the pinned edge relatively remote from the fold line, and a zigzag stitch formation binding the sections together in a substantially flat seam, said stitch formation piercing the fabric of the sections and their folded back edge portions along closely spaced parallel stitching lines located slightly beyond the edge folds.

10. A stitched garment seam construction comprising delicate garment fabric sections having folded back edge portions and disposed with their fold lines in abutting relation, the edge portions extending in opposite directions from the fold lines and each lying flat against its section on the normally concealed side thereof, and a zigzag stitch formation passing through the combined thickness of each section and its folded edge portion remote from the extremities of the edge portion, the several stitching lines being narrowly spaced from each other and disposed slightly back of the fold lines.

ROBERT GOLDSMITH.
